UNITED STATES PATENT OFFICE.

JOHN C. ROWAN, OF ATLANTA, GEORGIA, ASSIGNOR OF ONE-HALF TO WILLIS DOBBS,
OF ATLANTA, GEORGIA.

SPARK PLUG.

Application filed December 23, 1922. Serial No. 608,593.

To all whom it may concern:

Be it known that I, JOHN C. ROWAN, a citizen of the United States, residing at Atlanta, in the county of Fulton and State 5 of Georgia, have invented certain new and useful Improvements in Spark Plugs, of which the following is a full, clear, and exact description.

My invention relates primarily to spark 10 plugs to be used in connection with internal combustion engines and has for its object to provide such a device having a plurality of adjustable spark gaps by means of which the intensity of the spark may be 15 varied, so as to prevent fouling of the plug by superfluous oil and by which the general efficiency of the motor is increased.

A further object of the invention resides in the provision of a transparent casing for 20 enclosing the spark gaps, whereby the operation of the plug may be observed at all times.

Another object of the invention contemplates the use of a portion of one of the 25 electrodes as a tool for adjusting the spark gaps.

Other objects and advantages of the invention will be apparent from the following description when taken in connection 30 with the accompanying drawings, in which,

Figure 1 is a side elevation of the improved spark plug.

Figure 2 is a longitudinal section through the plug.

Figure 3 is an enlarged fragmentary section through the upper end of the plug, and

Figure 4 is a horizontal section taken on line 4—4 of Figure 3.

Referring to the drawing more in detail 40 the numeral 1 indicates the main body or shell of the plug which is exteriorly threaded at its lower end for securing in the body of the engine. This shell is interiorly threaded as indicated by numeral 2 for the 45 reception of the nut 3 by means of which the insulating porcelain 4 is clamped in place against the shoulder 5 of the shell 1. Gaskets 6 and 7 are interposed between the porcelain 4 and the nut 3 and shoulder 5 respectively to prevent injury to the porcelain.

The upper body of the plug comprises a casing 8 of glass or similar transparent material, preferably of conical form in order 55 to strengthen the same and also to allow

for the ready positioning of the usual spark-plug wrench. This casing is formed with a bead 9 at its lower end by means of which it is firmly clamped to the nut 3 by swaging over the portion 10 thereof. A packing 11 60 is disposed between the bead 9 and flange 10 which protects the casing from injury and also renders the joint gastight. A similar bead 12 is provided at the upper end of the casing 8 and has clamped thereon 65 the ferrule 13 with interposed gasket 14.

The shell 1 has permanently connected therewith the inwardly directed electrode 15 which is suitable spaced from the section 16 of the main electrode which is embedded 70 in the insulating porcelain 4. This porcelain is formed with a spherical cavity adjacent its upper end in which terminates the upper end of the main electrode section 16. Threadedly mounted in the bushing 18 carried by the porcelain 4 is the middle section 19 of the main electrode, which is provided with a kerf 20 in its end in order 75 that this section of the electrode may be rotated for longitudinal adjustment. 80

Threadedly mounted in the ferrule 13 is a sleeve 21 in which is slidably connected the upper or third section 22 of the main electrode. A coil spring 23 surrounds the lower portion of the section 22 and normally 85 holds the latter at the limit of its outward movement. A pin 24' prevents complete removal of the electrode section 22 from the sleeve 21. From this construction is is obvious that the point of the section 22 may 90 be adjusted to the proper position by adjusting the sleeve 21 within the ferrule 13, a nut 24 being provided for locking the sleeve 21 in adjusted position. A corresponding adjustment may be made of the 95 intermediate section 19 by pushing downwardly on the section 22 until its sharpened end 25 engages the kerf 20 in the electrode section 19, and then turning the section 22 in the proper direction by means of its 100 knurled end 26.

A nut 27 is threaded to the sleeve 21 for the purpose of securing the usual line wire (not shown) in electrical engagement with the plug. 105

In operation, if it is desired to change the length of the lower spark gap in the main electrode, it is only necessary to press inwardly on the section 22 until its end 25 engages in the kerf 20 and then turn the 110

same in the required direction. The engagement of the parts 20 and 25 and the adjusting operation may, of course, be observed through the transparent casing 8. 5 For adjusting the position of the main electrode the nut 24 is loosened and the sleeve 21 turned in the proper direction to move the point 25 to the desired position.

From the foregoing description it will be 10 seen that I have provided a spark plug having comparatively few parts and in which adjustable spark gaps are provided for intensifying the spark. Also that the 15 adjustments of these gaps may be made in full view and without the aid of tools.

In accordance with the patent statutes I 20 have described what I now believe to be the best embodiment of the invention, but I do not wish to be understood thereby as limiting myself or the scope of my invention as 25 many changes and modifications may be made therein without departing from the spirit of the invention, and all such I aim to include within the scope of the appended claims.

What I claim as new and desire to secure 30 by Letters Patent is:

1. In a spark plug, a sectional electrode including a spark gap, one of said sections 35 being longitudinally adjustable, and another of said sections being constructed and arranged for operating the adjustable section.

2. In a spark plug, a sectional electrode 40 including a plurality of spark gaps, two of said sections being adjustably mounted, and cooperating means on said adjustable sections whereby one of said sections may be 45 adjusted by the other section.

3. In a spark plug, a sectional electrode 40 including a plurality of spark gaps, one of said sections being longitudinally adjustable, means on another of said sections for adjusting the adjustable section, and resilient means normally holding said sections 45 apart.

4. In a spark plug, a sectional electrode including a plurality of spark gaps, two of said sections being adjustably mounted, cooperating means on said adjustable sections 50 whereby one section may be adjusted through the other section, and a coil spring encircling one of said adjustable sections and normally holding it in retracted position. 55

5. In a spark plug, an electrode comprising three spaced, longitudinally arranged sections, means for adjustably mounting the central section, means for adjustably mounting the upper section, said latter means including a sleeve adjustably mounted in the upper end of the plug and in which said upper section is longitudinally movable, cooperating means whereby one of said adjustable sections may be operated by the other adjustable section, and means normally holding said adjustable sections spaced apart. 60 65

6. In a spark plug, a sectional electrode including a spark gap, one of said sections 70 being longitudinally adjustable, another of said sections being constructed and arranged for operating said adjustable section, and a transparent casing surrounding the portion of the electrode including the spark gap, 75 whereby the manipulation of one section by the other may be observed.

JOHN C. ROWAN.
